Primary Examiner — Holly E Thurman*Assistant Examiner* — Altaira J Swangin(74) Attorney, Agent, or Firm — Rumit Ranjit Kanakia(57) CLAIM

The ornamental design for a wall mounted dry food dispenser, as shown and described.

DESCRIPTION

FIG. 1 is a perspective view of a wall mounted dry food dispenser showing my new design;

FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is a bottom view thereof.

The broken lines in the drawings depict portions of the wall mounted dry food dispenser that form no part of the claimed design.

1 Claim, 5 Drawing Sheets(56)
